CLAIM

The ornamental design for a box for shavers, as shown and described.

DESCRIPTION

FIG. 1 is a first perspective view of a first embodiment of an ornamental design for a box for shavers.

FIG. 2 is a second perspective view thereof showing the top of the box for shavers opened.

FIG. 3 is a third perspective view thereof showing the perforated segments partially separated from the box for shavers.

FIG. 4 is a fourth perspective view thereof and is similar to FIG. 2 showing an outline of a shaver to illustrate the environment.

FIG. 5 is a front view of the box for shavers of FIG. 1.

FIG. 6 is a back view thereof.

FIG. 7 is a left view thereof.

FIG. 8 is a right view thereof.

FIG. 9 is a top view thereof.

FIG. 10 is a bottom view thereof.

FIG. 11 is a first perspective view of a second embodiment of an ornamental design for a box for shavers.

FIG. 12 is a second perspective view thereof showing the top of the box for shavers opened.

FIG. 13 is a third perspective view thereof showing the perforated segments partially separated from the box for shavers.

FIG. 14 is a fourth perspective view thereof and is similar to FIG. 12 showing an outline of a shaver to illustrate the environment.

FIG. 15 is a front view of the box for shavers of FIG. 11.

FIG. 16 is a back view thereof.

FIG. 17 is a left view thereof.

FIG. 18 is a right view thereof.

FIG. 19 is a top view thereof.

FIG. 20 is a bottom view thereof.

FIG. 21 is a first perspective view of a third embodiment of an ornamental design for a box for shavers.

FIG. 22 is a second perspective view thereof showing the top of the box for shavers opened.

FIG. 23 is a third perspective view thereof showing the perforated segments partially separated from the box for shavers.

FIG. 24 is a fourth perspective view thereof and is similar to FIG. 22 showing an outline of a shaver to illustrate the environment.

(Continued)

FIG. 25 is a front view of the box for shavers of FIG. 21.
 FIG. 26 is a back view thereof.
 FIG. 27 is a left view thereof.
 FIG. 28 is a right view thereof.
 FIG. 29 is a top view thereof; and,
 FIG. 30 is a bottom view thereof.

The dash-dash broken lines represent perforations on the box for shavers and form a part of the claimed design. The dash-dot-dash broken lines illustrate the environment of the claim and form no part of the claimed design.
